UNITED STATES PATENT OFFICE.

ERNEST H. HENDERSEN, OF PHILADELPHIA, PENNSYLVANIA.

BOAT-LAUNCHING DEVICE.

1,121,499.

Specification of Letters Patent. Patented Dec. 15, 1914.

Application filed April 3, 1914. Serial No. 829,325.

To all whom it may concern:

Be it known that I, ERNEST H. HENDERSEN, a citizen of the United States of America, residing at Philadelphia, in the 5 county of Philadelphia and State of Pennsylvania, have invented new and useful Improvements in Boat-Launching Devices, of which the following is a specification.

This invention relates to devices for 10 launching boats and rafts, and particularly to the launching of such objects from a ship at sea.

Although in marine service ships are required to make provision for saving all of 15 the maximum number of passengers that a particular ship is permitted to carry, it has at times been found to be exceedingly difficult and in some cases even impossible to successfully launch a life boat or raft from 20 the vessel's side. This may be due to the normal ferocity of the waves, which tend to batter the smaller boat against the side of the larger one, or it may be due to the listing of the ship, causing the vessel to assume 25 a position out of plumb and thus making it impossible to lower a boat from the ordinary form of davits without the former engaging the adjacent side of the ship with attendant serious consequences, thus placing all of the 30 boats on one side out of possible commission.

The object of this invention is to provide a device which will overcome these and similar difficulties, and make possible the safe launching of all of the life boats carried by a vessel, substantially regardless of 35 the position of the latter, or of the condition of the sea.

Another object is to provide such a device, so constructed that when not in use, it occupies 40 a collapsed position out of the way and presenting a neat appearance.

Further objects and advantages of the invention are fully brought out in the following specification, when read in conjunction 45 with the accompanying drawings, in which:—

Figure 1 is a side elevation of a portion of an ocean liner equipped with the device in its preferred form; Fig. 2 is a transverse 50 section of the same, showing the device in folded position; Fig. 3 is a top plan view of the same in extended position; Fig. 4 is an enlarged detail section of the means for maintaining the device rigidly in lowered 55 position; and Fig. 5 is a similar view of the chain.

Referring to the drawings, the invention in its preferred form, as shown in Figs. 1 and 2, comprises a frame structure, consisting of substantially parallel side members 1, 60 pivotally secured by members 2 to the hull of a ship at a point above the water line, and having their outer ends joined by a member 4 secured to the same. Also secured to the side members and adjacent to their free ends 65 are stout but flexible cables or chains 5, likewise secured to the ship's hull at the same elevation as the pivotal supports 2, said cables being operative to hold the frame substantially rigidly laterally and against 70 any transverse movement, and simultaneously acting as guards.

Secured to the end members 4 of the frame is a pair of flexible cables or chains 6, the same being led over anti-friction supports 7 across the uppermost deck of the ship and thence on the far side to any suitable form of windlass 8, the same being operated either manually or by motive power. The chains or cables 6 are provided, as shown in Fig. 5, with sectional overlapping metallic plates 9, having downwardly projecting lugs 11 which are pivotally secured to the series of the chain links, or to the cables at equal distances apart. When the frame is in elevated position, dogs or pawls 13, secured to the side members of the same at 14, lie substantially parallel to said members, while on the lowering of the frame into its extended position, the springs 15, secured to 80 said members 1 and to the dogs 13, force the latter downwardly so that their free ends engage the teeth 16 of a rack bar 17, in turn secured to the side plates of the ship. Upon lowering the frame to its extended 90 position, the flexible slide or runway thus formed and comprising the chains and plates above described, passes outwardly over the supports 7 until the frame assumes its lowermost position, where it is automatically held by the dogs 13, after which the windlass 8 is tightened, to insure the tautness of the inclined way or plane.

Suitably positioned upon the uppermost parts of the liner or other ship to which the 100 device is applied, are any desired number or kind of life boats 20, or rafts, which on being filled with their allotment of passengers, are permitted to slide down the inclined plane and into the water, the boats or rafts 110 being controlled in their downward course in any desired manner. In this way the

launching of the life boats from a ship is greatly facilitated when the severity of the waves would practically, if not entirely prevent the same.

5 Only one form for the embodiment of the invention has been minutely described, but the invention in its broad interpretation should anticipate all devices within its spirit and within the scope of the appended claims.

10 I claim:—

1. A boat launching device, comprising a frame mounted upon a vessel, means to automatically maintain the same in operative position, and a flexible inclined plane secured to said frame and adjustably secured to said vessel.

15 2. A boat launching device, comprising a frame pivotally mounted upon the side of a vessel, means to automatically maintain the

same in operative position, a flexible inclined plane secured to said frame, and a windlass to adjustably secure the other end of said plane to said vessel.

3. A boat launching device, comprising a frame pivotally secured to the side of a vessel, a spring-operated dog and a rack to automatically maintain the same in operative position, a flexible inclined plane secured at one end to said frame and comprising a pair of flexible members carrying overlapping metallic plates, and a windlass to adjustably secure said members to the vessel.

In testimony whereof I affix my signature in presence of two witnesses.

ERNEST H. HENDERSEN.
